United States Patent Office

Des. 232,259

Patented July 30, 1974

232,259

EYEGLASS CASE OR SIMILAR ARTICLE

Robert G. Brown, deceased, late of East Alton, Ill., by Gertrude T. Brown and Robert C. Brown, Ridgewood,
N.J., and Gene Louise Grant, Cheyenne, Wyo., heirs, assignors to Magni-Case, Inc.

Filed Oct. 8, 1970, Ser. No. 25,400

Term of patent 14 years

Int. Cl. D16—08

U.S. Cl. D57—1

FIG. 1 is a front elevational view of an eyeglass case or similar article showing the new design;

FIG. 2 is a rear elevational view thereof;

FIG. 3 is a side elevational view thereof;

FIG. 4 is a top plan view thereof; and

FIG. 5 is a bottom plan view thereof.

What is claimed is:

The design for an eyeglass case or similar article, substantially as shown.
